UNITED STATES PATENT OFFICE.

HENRY B. HOLLIS, OF NEW YORK, N. Y.

TABLE OR DESK FOR HOLDING DIES.

SPECIFICATION forming part of Letters Patent No. 695,051, dated March 11, 1902.

Application filed March 2, 1900. Renewed August 12, 1901. Serial No. 71,814. (No model.)

To all whom it may concern:

Be it known that I, HENRY B. HOLLIS, a citizen of the United States, and a resident of New York, in the county of New York and State of New York, have invented a certain new and useful Table or Desk for Holding Dies, of which the following is a specification.

My invention relates generally to desks, and more particularly to desks for holding dies to be used in restaurants, hotels, &c., for printing checks and account-sheets, such as shown, for instance, in Patent No. 626,237.

Heretofore it has been customary to provide an independent receptacle properly partitioned for the storage of the dies used in printing the checks used in restaurants, hotels, &c. This construction, however, has been found to be unsatisfactory in many ways and notably in the fact that if the receptacle containing the dies is upset the contents of the same is thrown on the floor, and the dies being thus scattered it requires considerable time to replace same in their regular order in the said receptacle. Moreover, in thus being upset the dies are frequently damaged, and consequently have to be replaced at considerable expense and annoyance.

To obviate the above-mentioned disagreeable features is the object of my invention; and to that end my invention consists of the hereinafter-described combination of co-operative elements.

While the construction shown in the accompanying drawings is believed to be the one best suited to carry out the purposes of my invention, constructional changes may of course be made without departing from the spirit of my invention.

In the said drawings, Figure 1 is a perspective view of a desk embodying my invention. Fig. 2 is a perspective view of the removable pad. Fig. 3 is a sectional view on the line *a b* of Fig. 1. Fig. 4 is a sectional view on the line *c d* of Fig. 2.

Similar letters of reference indicate corresponding parts in the different views.

I shall describe a desk-table for holding dies embodying my invention and afterward point out the novel features in the claim.

1 indicates a support, herein shown as a desk

or counter of any suitable construction, provided with a flat or slanting top 2.

3 is an upright aperture in the top 2 of the support, provided at the bottom with a continuous surrounding horizontal groove 4. 55 This groove 4 extends through the front wall 5 of the aperture—here the front of the desk—so as to permit the insertion into said groove of the independent and removable plate 6. The latter is formed with a surrounding edge 60 or frame 7, adapted to rest and be housed within the groove 4, and within this frame is secured an inking-pad 6^a. A framework of cells in pigeonholes 8 is now inserted in the aperture 3, the parts being so constructed 65 that the upper surface 8^a of the framework is flush with the top 2 of the support, so as not to interfere with the use of the latter as a desk, while the pad 6^a of the plate 6 forms a bottom for all the cells, so as to make it a receptacle for the dies 9. These are provided 70 at their lower edges with type or symbol-faces, which are thus caused to rest on the inking-pad 6^a, so that the printing-surfaces are continually kept inked and in condition for constant use. The upper ends or handles of the dies, as shown, will project out of the cells, 75 so that they may easily be grasped by the checker.

The advantages of the construction as 80 pointed out herein over the independent receptacle are numerous, it being, for instance, a much easier matter to renew the inking-pad when it gives out than in receptacles where the bottom is formed with the side 85 walls.

My construction forms an easy, simple, inexpensive, stable, and firm means for storing the dies and in practical utility far surpasses the independent die-box. 90

Having thus described my invention, what I claim is—

The herein-described receptacle for dies, the same comprising a substantially flat support having in its top an upright aperture 95 which is provided at its bottom with a surrounding groove opening out through the front of said support, a plate removably inserted from the front into said groove and consisting of a frame surrounding and at 100

tached to an inking-pad which latter is of the size of said aperture, and a framework of cells removably inserted in the aperture and of a depth sufficient to stand flush with the top of the support when it rests upon said plate, all substantially as herein shown and described.

Signed at New York, in the county of New York and State of New York, this 28th day of February, A. D. 1900.

HENRY B. HOLLIS.
